US0D1013731S

(12) **United States Design Patent** (10) **Patent No.:** **US D1,013,731 S**
(45) **Date of Patent:** **** Feb. 6, 2024**

(54) **PUMP DEVICE**

(71) Applicant: **Zhejiang Sanhua Automotive Components Co., Ltd.**, Hangzhou (CN)

(72) Inventors: **Binhao Fu**, Zhejiang (CN); **Jun Zhang**, Zhejiang (CN); **Longji Cai**, Zhejiang (CN)

(73) Assignee: **Zhejiang Sanhua Automotive Components Co., Ltd.**, Hangzhou (CN)

(**) Term: **15 Years**

(21) Appl. No.: **29/765,911**

(22) Filed: **Jan. 12, 2021**

(30) **Foreign Application Priority Data**

Nov. 3, 2020 (CN) 202030659145.9

(51) **LOC (14) Cl.** **15-02**

(52) **U.S. Cl.**
USPC **D15/7**

(57) **CLAIM**

The ornamental design for a pump device, as shown and described.

DESCRIPTION

FIG. 1 is a top, front, right side perspective view of a pump device according to the present application, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dot-dash broken lines represent boundaries of the claimed design and form no part of the claimed design. The dash-dot broken lines in the drawings depict portions of the pump device that form no part of the claimed design.

1 Claim, 7 Drawing Sheets
